UNITED STATES PATENT OFFICE.

LAURITS DINESEN, OF MINNEAPOLIS, MINNESOTA, ASSIGNOR TO PERFECTION
MANUFACTURING COMPANY, OF MINNEAPOLIS, MINNESOTA, A CORPORA-
TION OF MINNESOTA.

CONTINUOUS-ACTING PUMP.

1,286,958.

Specification of Letters Patent. Patented Dec. 10, 1918.

Application filed February 23, 1915. Serial No. 9,901.

To all whom it may concern:

Be it known that I, LAURITS DINESEN, a citizen of the United States, residing at Minneapolis, in the county of Hennepin and 5 State of Minnesota, have invented certain new and useful Improvements in Continuous-Acting Pumps; and I do hereby declare the following to be a full, clear, and exact description of the invention, such as will 10 enable others skilled in the art to which it appertains to make and use the same.

My invention relates to improvements in continuous acting pumps, especially adapted for use as a vacuum or suction pump to produce a partial vacuum or suction in a milking 15 apparatus, or similar apparatus.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

25 Figure 1 is a plan view of the improved pump, some parts being broken away, and some of the exposed parts being shown in section; and,

Fig. 2 is a view principally in longitudinal 30 vertical section, taken on the line X^2-X^2 of Fig. 1.

The numeral 1 indicates a pair of diametrically disposed cylinders, supported on end castings 2 and connected by a cylindrical 35 crank casing 3, with its axis extended at right angles to the axis of said cylinders. Formed in the top of the crank casing 3 is an exhaust port 4, open to the atmosphere and having mounted therein a muffler 5. 40 This muffler, as shown, is in the form of a plurality of vertically spaced wooden blocks, each having formed therein a plurality of circumferentially spaced openings 6, that are offset with respect to the openings in 45 adjacent blocks.

The open outer ends of the cylinders 1 are closed by heads 7, each having formed therein a valve chamber 8 with a spider bearing bracket 9. In each bearing bracket 50 9 is mounted the stem of a spring closed valve 10, arranged to open under the suction stroke of the piston. These valves 10 are seated in seats 11 formed in the inner faces of the heads 7, and normally closing the

valve chambers 8 with respect to the cylinders 1. Each valve chamber 8 is connected to the suction pipe, or conduit 12, of a milking apparatus, (not shown) by a branch pipe, or conduit 13.

Mounted in the cylinders 1 is a duplex piston 14, the heads of which are connected by a pair of horizontally spaced webs 15, having formed therein a pair of diametrically opposite slots 16 extended longitudinally of said piston 14. In each head of the piston is mounted a flanged conduit 17, having a transversely extended spider bearing bracket 18. These conduits 17 afford communication between the cylinders 1 and the interior of the piston 14, and the laterally spaced webs 15 and slots 16 afford constant communication between the interior of the piston 14 and the crank casing 3. The conduits 17 are normally closed by spring closed valves 19, seated in seats 20, formed 75 in the inner ends of said conduits, and having their stems mounted in the bearing brackets 20.

Journalized in bearings 21, formed in the crank casing 3, is a horizontally extended shaft 22, which is extended axially through said crank casing, and through the slots 16 formed in the webs of the piston 14. To one end of the shaft 22 is keyed a driving pulley 23, over which runs a belt (not shown), and to the intermediate portion of said shaft is keyed an eccentric 24, which works between the webs 15 and the piston 14. Rigidly secured to the piston 14 is a pair of horizontally spaced, vertical cross-head guides 25; located, one at the junction of each head of the piston 14 with the webs 15. These cross-head guides 25 extend transversely through the piston 14, and have mounted thereon for vertical sliding movement a cross-head 26, in the form of an eccentric strap, within which works the eccentric 24. Obviously, under the constant rotation of the eccentric 24, a reciprocating motion is imparted to the piston 14, and a vertical sliding movement is imparted to the cross-head 26 on the guides 25.

Under the oscillatory movement of the piston 14, the valves 10 are alternately opened under the suction stroke, thereby 105 producing a partial vacuum or suction in the conduit 12. Under the compression stroke of the piston 14, the valves 19 are alternately

opened to release the compressed air in the cylinders 1, and discharge the same through the exhaust port 4.

As is evident by reversing the valves 10 and 19, so that the valves 10 will open under the compression stroke of the piston, and the valves 9 open under the suction stroke thereof, the improved pump may be used in connection with a compressor.

10 What I claim is:

1. The combination with a pair of opposite cylinders, and a casing connecting the same, of a cylindrical piston having, on its ends, piston heads working in the cylinders, 15 said piston also having formed therein a horizontally alined pair of longitudinal slots and a vertically alined pair of longitudinal slots, a driving shaft journaled in the casing and extending through the horizontally alined slots, a pair of laterally spaced guide rods extending transversely through the piston at the ends of the vertically alined slots, 20 an eccentric strap carried by the guide rods and working in the vertically alined slots, and an eccentric mounted in the eccentric strap and secured to the driving shaft.

25

2. The combination with a pair of opposite cylinders, and a casing connecting the same, of a cylindrical piston having, on its ends, piston heads working in the cylinders, 30 said piston also having formed therein a horizontally alined pair of longitudinal slots and a vertically alined pair of longitudinal slots, a driving shaft journaled in the casing and extending through said horizontally 35 alined slots, vertically alined pairs of segmental seats formed in the piston and opening into the ends of the vertically alined slots, a pair of guide rods extending transversely through the piston and having their 40 ends anchored in said seats, an eccentric strap carried by the guide rods and working in the vertically alined slots, and an eccentric mounted in the eccentric strap and secured to the driving shaft.

In testimony whereof I affix my signature in presence of two witnesses.

LAURITS DINESEN.
